FIG. 4

FIG. 5

FIG. 7

UNITED STATES PATENT OFFICE.

FRANK B. ALLEN, OF CYNWYD, PENNSYLVANIA, ASSIGNOR, BY MESNE ASSIGNMENTS,
TO FRANK H. DUNBAR.

ASH GATE.

Original application filed June 28, 1922, Serial No. 571,404. Divided and this application filed December 28, 1923. Serial No. 683,104.

To all whom it may concern:

Be it known that I, FRANK B. ALLEN, a citizen of the United States, residing at Cynwyd, in the county of Montgomery and 5 State of Pennsylvania, have invented certain new and useful Improvements in Ash Gates, of which the following is a specification.

My invention relates to hopper construction, particularly to construction of the bottom portion of hoppers having bottom discharge openings, which portion is commonly called the "gate." It especially relates to gates for such hoppers which are to receive the ashes from large heating units. It also 10 relates to so-called gate construction for hoppers having two or more spaced bottom discharge openings.

For the purpose of this specification the term "gate" is understood to mean the structural parts comprising the bottom portion of a hopper of the type above described and including, among other parts, (1) a stationary member surrounding each discharge opening in the hopper bottom and 20 constituting more or less definite parts of the downwardly extending hopper walls, (2) a movable door for each discharge opening, and (3) a frame for supporting and means for operating the doors.

One object of my invention is to construct 30 a hopper gate comprising stationary members for two or more discharge openings, a frame for two or more stationary members having portions adapted to serve as tracks for door-supporting wheels and a door for each opening.

Another object is to construct a hopper gate having a door provided with longitudinally unaligned supporting wheels, and a 40 frame having inner and outer portions adapted to serve as tracks for the unaligned door wheels.

Another object is to construct a hopper gate frame having inner portions between 45 adjacent discharge openings which serve as rails for the wheels on the rear or adjacent ends of the doors for such openings and other outer portions which serve as rails for the wheels on the front or remote ends of 50 such doors.

Another object of my invention is to provide downwardly projecting nozzles on the stationary members to which a hose may be attached for the purpose of washing out any

ashes or clinker that may have found their 55 way into and remained in the troughs.

Another object of my invention is to provide a simple and yet rugged ash gate construction such that the stationary members and frame may be built as a unit and combined with an operating cylinder thereon for the doors, so that when completed the whole unit may be shipped from the point of manufacture to the place where it is to be attached to the bottom of an ash hopper to 60 which it may be bolted or secured in any suitable manner.

Another object of my invention is to provide other details of improvement tending to increase the efficiency and serviceability 65 of an ash gate of the above described character.

To accomplish the foregoing and other useful ends, my invention makes use of means hereinafter more fully set forth and 70 claimed.

Referring to the accompanying drawings: Figure 1 is a top view of one form of gate embodying my invention.

Fig. 2 is a side view in elevation and partly in section of the gate shown in Figure 1, the section being taken on line 2—2 of Figure 1.

Fig. 3 is an end view in elevation, partly in section, of the gate and lower part of the 85 hopper, the section being taken on line 3—3 of Figure 1.

Fig. 4 is a sectional view of the gate taken on line 4—4 of Figure 1.

Fig. 5 is a top view of the door without 90 the frame and showing the troughs on the door and the stationary trough.

Fig. 6 is a view of the door and stationary trough taken on line 6—6 of Figure 5.

Fig. 7 is a sectional view taken on line 95 7—7 of Fig. 5.

Referring more in detail to the drawings, and more particularly to Figure 1, it will be seen that the frame has two main girders 2 and 3, forming the longer sides of the gate frame which girders are connected near the middle by the cross ties 4 and 5. The ends of the girders shown at the left side of the figure are held together by the angle iron tie 6, while the other ends, shown in the right-hand part of the figure are held together by the angle iron tie 7. Within this frame are secured hopper stationary members 8, one

- for each hopper discharge opening, which in the form shown are each composed of a cast iron casting. The inner side walls 8^a of member 8 constitute the bottom portions of
- 5 the downwardly extending hopper walls about the discharge openings as shown in Fig. 3 and co-operate with doors 9 and 10 to form a substantially airtight closure for the opening.
- 10 Each of the doors 9 and 10 is provided with two sets of wheels, one set being an inside set and the other being an outside set, with respect to the frame structure. The inside set of wheels are the wheels 11, and
- 15 the outside set are the wheels 12. The wheels 12 are arranged to run on outside flanges 13 of members 2 and 3 respectively while the inside set of wheels 11 are arranged to run on an auxiliary set of flanges
- 20 14. These flanges 14 are parts of angle iron pieces 14^a which are located on the inside of the frame, see Fig. 4. These angle iron pieces 14^a are only long enough to cover the space necessary to accommodate the inside
- 25 wheels of the door 10, and the inside wheels of the door 9. It will be understood, of course, that the door 9 has likewise its inner set of wheels 16 and its outer set of wheels 17.
- 30 The method of mounting the wheels 11 and 16 is shown in Fig. 4. Suitable spindles 23 are secured to the rear ends of the doors upon which spindles the wheels 11 and 16 are suitably mounted to rotate.
- 35 The wheels 12 are mounted a little differently. A suitable arm 24 is secured to the lower part of the front end of door 10, Fig. 3. This arm has a projecting portion that passes under the girder 3, it being cut away
- 40 as shown in Fig. 3, for this purpose. On the right hand of this arm a suitable spindle 25 is clamped to the end of the arm 24 by means of bolts 26. On this spindle the wheel 12 is secured to rotate. It will be
- 45 seen that the wheel 12 is on the inner side of the spindle securing bolts 26 and rolls along the flange 13 of the girder 3.
- On the opposite side of the door there is another arm 27 similar to the arm 24 on
- 50 which the other wheel 12 is similarly mounted. It will be understood that the wheels 17 are similarly mounted on arms under the door 9, similar to arms 24 and 27, and that the wheels 12 and 17 run on flanges 13 of members 2 and 3.
- 55 On the under side of the frame and bolted to the cross ties 4 and 5, I secure the cylinder 28, Fig. 2, which is provided with two pistons, each piston having a piston rod secured thereto. One of the rods 29^a is secured to the yoke 30 under and attached to the door 9, while the other piston rod 29^b is secured to the yoke 31 under and attached to the door 10. It will be seen, therefore,
- 60 that by operating the piston rod 29^b, the

door 10 may be opened as shown in Fig. 2, the piston being indicated at the extreme end of its stroke, by operating the piston in a reverse direction the door 10 may be closed.

In the operation of the door 10, the wheels 11 will roll along the flanges 14 which serve as tracks while the wheels 12 will roll along the outer flanges 13 of the girders 2 and 3. In a similar manner the piston rod 29^a will operate the door 9. It will be understood, of course, that when the door 10 is open, the door 9 must be closed or substantially so, and vice versa, due to the limited space between the openings.

Since doors 9 and 10 are alike in substantially all respects only one will be described in detail. Door 10 is formed with upstanding flanges or projections 10^a within which lining bricks or material (not shown) may be positioned. Along the opposite sides and rear end 10^a, the door is extended laterally and provided with upstanding flanges 10^b which extend above the top of flanges 10^a and the top of the door proper, all as is clearly shown in Figs. 1, 3, 5 and 6. Also, as will be noted from these figures, the flanges 10^b extend above the bottom edge of inner side walls 8^a of stationary members 8. Flanges 10^a and 10^b co-operate to form troughs along the rear end 10^a and opposite sides of the door, the rear end trough being connected with the side troughs, for example, by enclosed passages 19^c cored out in the rear corners of the door. The troughs thus formed constitute, when joined together, a channel which has been designated on the drawings as 19, and which is adapted to collect liquid passing through the hopper and off the three sides of the door and to conduct such liquid to the front end 10^c of the gate where it may be discharged into a trough 18. The channel 19 preferably has the highest point of its bottom wall along the rear end of the door, as at the point indicated by 20 in Fig. 4. From this point the bottom wall of the end trough slopes or inclines downwardly toward each side trough A and B as shown in Fig. 4, and the bottom walls of troughs A and B each slope or incline downwardly from the end trough toward the front end of the door, as is clearly shown in Fig. 7.

These side troughs A and B terminate in forwardly and downwardly projecting spouts 22, which are located above the trough 18 when the door is in closed position with respect to member 8 and the hopper discharge opening.

Projecting down from the upper side of the stationary member 8, Figs. 1 and 2, I provide a nozzle 33, which is located at an angle sloping in the direction of the trough 18. The object of this nozzle is to enable a hose or similar means connected to a source of water under pressure to communicate

with the nozzle for the purpose of scouring out the side troughs in the door in the event that ashes or other material accumulates therein. There is one such nozzle on either 5 side of the member, one for the trough A and another for the trough B. A similar set of nozzles are provided for the other door. It will be understood that any number of these nozzles may be located anywhere above 10 the trough 19 or stationary trough 18.

A gate of this construction is rugged and rigid. It is a complete unit, may be assembled at the factory and as a unit picked up by a crane without any danger of warping 15 or breaking. It may then be conveyed to the plant where the ash hopper is located and bolted into position, as indicated in Fig. 3. Some of the bolts by means of which the frame is bolted in the ash hopper 34, Fig. 3, 20 are long enough to extend from the flange 13 up to the flange 35. Other of the bolts are shorter. Along the girders 2 and 3, suitable brackets 36 are provided and bolts are used to fasten these brackets to the flange 35. The 25 brackets 36 are of course suitably riveted to the girders 2 and 3.

It will be noted that I have provided an ash gate of simple yet durable construction, which can be assembled as a unit and shipped 30 to the place of installation and yet a construction which contains no unnecessary expensive parts and may be cheaply manufactured.

It will be observed that the arrangement 35 of wheels on the ash doors is such that they are all protected from contact with ashes. The wheels 12 and 17 which travel past the ash discharge openings are on the outside tracks and thoroughly protected from ashes while the wheels 11 and 16 do not pass the 40 ash openings and may therefore operate on inside tracks, since these tracks do not extend beneath the openings and therefore cannot collect ashes.

This application is a division of my co- 45 pending application Serial No. 571,404 filed on or about June 28, 1922.

It will also be observed that I have provided water collecting troughs A and B along opposite sides of the door which are 50 substantially straight and open topped from end to end. When such troughs are not substantially straight or when they are covered for part of their length ashes may lodge in the troughs and interfere with or entirely 55 stop the flow of water therein. In my door however the troughs are wide, straight and open for the full width and length thereof insuring against lodging of material therein and providing easy accessibility for cleaning. 60 The spouts 22 at the ends of troughs A and B are short and easily accessible for cleaning and may be made of such size that no solid material from the troughs will stop or clog them.

Having thus described a practical embodi-

ment of my invention, so that others skilled in the art may practice the same, what I desire to secure by Letters Patent is defined in the claims, it being understood that changes, alterations or modifications not involving inventions may be made in the structural details and parts herein shown, without departing from the spirit and scope of my invention.

What I claim is:

1. A gate construction for a hopper having a plurality of bottom openings, comprising a gate frame having a pair of side members located on opposite sides of and extending continuously past the said openings, cross members joining the said side members, a stationary member for each bottom opening carried between the said side members and between two cross members in position to cooperate directly with the adjacent door in forming a closure for the opening, a door for each opening movably mounted on the said side members, and a multiple piston cylinder supported by the said cross members and located between the said side members and having a piston operatively connected to each of the said doors.

2. A gate construction for a hopper having a plurality of spaced bottom openings, comprising a gate frame having side members located on opposite sides of and extending continuously past two adjacent openings, cross members joining the said side members between the said openings, stationary members carried by the said frame and adapted to surround said openings respectively, a door for each opening movably mounted on the said frame and cooperating directly with the adjacent stationary member to form a closure for the said opening, and a cylinder supported by the frame between the said side members and between the said openings and having two pistons, each piston being operatively connected to a door to actuate the same.

3. A gate construction for a hopper having a plurality of bottom openings, comprising a gate frame having side members located on opposite sides of and extending continuously past each of said openings, cross members joining the said side members between the said openings, a stationary member for each opening between the said side members and secured thereto in position to cooperate directly with the adjacent door in forming a closure for the opening, a door for each opening movably mounted on the said frame, and means carried by the said cross members between the said side members for actuating the said doors into and out of closed position with respect to the said openings.

4. A gate construction for a hopper having a bottom opening, comprising a gate frame having side members located on op-

- posite sides of and extending continuously along and beyond the opening, each side member having inwardly and outwardly extending flanges, a door for the opening having a set of wheels adapted to run on the said outwardly extending flange and another set of wheels adapted to run on the said inwardly extending flange, and means for actuating the door.
10. 5. A gate construction for a hopper having a plurality of bottom openings, comprising a gate frame having side members located on opposite sides of and extending continuously past the openings and each having an outwardly extending flange, a member having an inwardly extending flange secured to each of said side members, a door for each opening, each door having a set of wheels adapted to run on the said outwardly extending flanges and another set of wheels adapted to run on the said inwardly extending flanges, and means for actuating the doors.
6. A gate construction for a hopper having a bottom opening, comprising a gate frame having side members located on opposite sides of and extending continuously past the said opening, cross members joining the said side members, a stationary member carried by the said frame and adapted to surround the opening, a door for the opening co-operating directly with the said stationary member to form a closure for the said opening, the said door having wheels engaging the side members, and a cylinder, supported by the cross members having a piston operatively connected to the door to actuate the same.
7. A gate construction for a hopper having a bottom opening, comprising a gate frame having side members located on opposite sides of the opening, each side member having inwardly and outwardly extending flanges, a door for the opening having a set of wheels adapted to run on the said outwardly extending flanges and another set of wheels adapted to run on the said inwardly extending flanges, and means for actuating the door.
8. A gate construction, for a hopper having a bottom opening, comprising a gate frame having side members located on opposite sides of the opening, each side member having inwardly and outwardly extending flanges, a door for the opening having inner and outer sets of wheels on its opposite sides adjacent to the rear and front ends respectively adapted to run on the said flanges, the said door having substantially straight open topped water collecting troughs along opposite sides thereof, with the discharge therefrom at the end of the door adjacent to said outer wheels, and means for actuating the door.
9. A gate construction, for a hopper having a bottom opening, comprising a stationary member adapted to be secured to the hopper and surrounding the opening, said member having a depending flange, inner and outer flanges operatively connected to the said depending flange on opposite sides thereof, a door having in relation to said depending flange, inner and outer sets of supporting members adjacent to opposite ends of the door, the said members being adapted to be supported by and to move on the said inner and outer flanges, the said door having water collecting troughs formed along opposite sides thereof with their discharge ends at the end of the door adjacent to said outer door supporting means, and means for actuating the door.
10. A gate construction for a hopper having a bottom opening, comprising a stationary member adapted to be secured to the hopper and surrounding the said opening, the said member having inner and outer flanges operatively connected thereto, a door having adjacent to its rear and front ends respectively, inner and outer sets of supporting members adapted to engage and move on the said inner and outer flanges, the door being provided along opposite sides thereof with substantially straight water collecting troughs adapted to discharge water at the front end of the door, the said troughs being open topped for substantially their entire length.
11. A gate construction, for a hopper having a bottom opening, comprising a stationary member adapted to be secured to the hopper and surrounding the said opening, said member having a depending flange, inner and outer flanges operatively connected to said depending flange, a door having adjacent to its rear and front ends respectively inner and outer sets of roller supporting members adapted to engage with and move on said inner and outer flanges, the said door being provided with troughs along two opposite sides thereof, the said troughs being disposed vertically above the said inner flanges when the door is in an open position.

In testimony whereof I hereunto affix my signature this 12th day of December, 1923.

FRANK B. ALLEN.
